United States Patent Office

Des. 209,407
Patented Nov. 28, 1967

209,407

CABINET

Andrew L. Gilmour, New York, N.Y., assignor to Steel-case, Inc., Grand Rapids, Mich., a corporation of Michigan

Filed Jan. 19, 1966, Ser. No. 682

Term of patent 14 years

(Cl. D33—19)

FIG. 1.

FIG. 2.

FIG. 3.

FIG. 1 is a perspective view of a cabinet embodying my new design, in which the front and rightward side are shown:

FIG. 2 is a perspective view similar to FIG. 1 but from an elevated position, showing the top of the cabinet also; and

FIG. 3 is a perspective view similar to FIG. 1, but showing the left side and front thereof.

The rear of the cabinet is substantially plain.

I claim:

The ornamental design for a cabinet, substantially as shown and described.
